UNITED STATES PATENT OFFICE.

JOSEPH W. ANTHONY, OF LYNN, MASSACHUSETTS.

LEATHER-FOLDING MACHINE.

Application filed March 23, 1918. Serial No. 224,224.

To all whom it may concern:

Be it known that I, JOSEPH W. ANTHONY, a citizen of the United States, and a resident of Lynn, county of Essex, and State of Massachusetts, have invented an Improvement in Leather-Folding Machines, of which the following is a specification.

My invention relates to machines for folding the edges of a material formed of leather or of flexible fabric, and is intended as an improvement over the machines disclosed and claimed in my applications, Serial No. 79,205, filed February 18, 1916, Serial Nos. 155,343, 155,344 and 155,345, filed March 16, 1917.

The machine with which the present invention is concerned is primarily adapted for the folding of material for book covers in which the cover has four substantially parallel filled sides and, generally, rounded corners, although it is obvious that the articles other than book covers may be folded in the machine.

In view of the great number of different sizes of book covers it is desirable that one machine be capable of forming all or, at least, a large number of parts special for each separate size.

Consequently, an object of my invention is in the provision of a machine for folding the edges of material whereby a number of different sizes of material may be folded to differing dimensions in the machine with the provision of but a minimum number of parts special to each dimension of fold.

The means whereby I accomplish this object of my invention is in making adjustable the various elements of the machine adapted for operation upon the material, whereby said elements may be relatively moved or whereby certain elements of the machine may be removed and others of differing dimensions substituted to condition the machine for the folding of material to differing dimensions.

Another object of the present invention is to provide means whereby four sides of the material may be folded, or whereby there may be a continuous folded edge extended entirely around the material.

A further object of the present invention is in the provision of means for the corner folding of the material in which the corner is given a rounded or curved edge.

In addition to the folding of the material in a continuous edge, provision is also made for the creasing or ornamental marking on the finished side of the article, inset from the edge thereof. 55

The creasing means, as in the former applications, comprises a creasing iron adapted to be engaged with the material to form the crease, and a further object of the present invention is to so arrange the creasing means that it may be adjusted to form an ornamental marking on material folded to various dimensions. 60

As in my former inventions, the machine comprises clamping plates between which the material is held during the folding operation, forming plates to define the folding edge, wipers to fold the edge and a creasing iron to form the crease or ornamental marking in the obverse side of the article. 70

Fig. 1 is a side elevation of the machine embodying my invention.

Fig. 2 is a plan view of Fig. 1.

Fig. 3 is a partial sectional view along lines 3—3 of Fig. 2. 80

Fig. 4 is a sectional plan view, with certain elements of the machine removed, of the operating ring.

Fig. 5 is a detail of the cam for operating the presser head. 85

Fig. 6 is a detail of the cam for operating the creasing iron.

Fig. 7 is a plan view of the creasing iron.

Fig. 8 is a side elevation of the creasing iron. 90

Fig. 9 is a detail of the table support and creasing iron adjusting means.

Fig. 10 is a sectional detail of the adjustable wiper supports.

Fig. 11 is a plan detail of Fig. 10, showing a corner wiper. 95

Figs. 12 to 15 inclusive are details of a corner wiper.

Fig. 16 is a sectional plan view on lines 16—16 of Fig. 17, showing the presser head with the forming plates. 100

Fig. 17 is a sectional view on lines 17—17 of Fig. 16.

Fig. 18 is a detail of the presser head with a forming plate in withdrawn position. 105

Figs. 19 and 20 are details of a forming plate locking means.

Figs. 21 to 23 inclusive are diagrammatic views showing the relative operation of the side and corner wipers.

Fig. 24 is a view of the article operated on, showing the folded edges.

Fig. 25 is a reverse view of Fig. 24, showing the crease or ornamental marking.

As here shown, the component parts of the machine are mounted upon the bed or frame 30. The machine is driven by an electric motor 31 disposed at one end of said bed or table, which is belted to a counter-shaft 32 arranged beneath the table and which, in turn, drives a shaft 33 arranged above the bed 30 in suitable bearings.

Clutching means are provided whereby the machine may be operably connected with the motor or disconnected at the will of the operator. Said means include a cone 34 fixed to said shaft 33 arranged in the clutched condition to fit within the tapered surface of a pulley 35 which is loosely arranged on said shaft 33 and belted to the counter-shaft 32. A clutch control lever 36 is arranged at the front of the machine and a rod 37 is extended from said lever through said bed 30 to a point adjacent said pulley and terminates in a block 38, which is in engagement with a pivoted forked lever 38' in rotatable engagement with said pulley 35. A movement of said clutch lever 36 from one position to another position serves to regularly move said rod 37 to rock said pivoted lever 38' and consequently move said pulley 35 into engagement with the cone 34 fixed to the shaft 33 or away from engagement with said cone to thereby operably connect said shaft with the motor or disconnect it from the motor.

Other clutching means, shown in the drawings but not necessarily described, are provided whereby the machine may be moved, at the control of an operative, through a single complete operation.

The shaft 33 is connected through gears 39 and 40 with the shaft 41 which carries the cam 42, which controls the operation of the various parts of the machine. This arrangement of drive from the motor to the shaft 41 provides means for reducing the speed of the motor to a value suitable for the operation of the machine.

The cam 42 through which the various operations of the component parts of the machine are performed, has dwell portions 43, which permits the angular rotation of the cam without operation of the mechanism; and active portions 44 arranged to cause the function of the various parts of the machine. During the period in which that part of the machine controlled by the cam is in one of said dwell portions 43, the various parts of the machine are arranged to be in their unoperated position, and the folded material may be removed from the

machine and a new piece of material inserted for folding while during the period the aforesaid part is in the other dwell portion of the cam the folded material is arranged to be pressed and creased.

70

A cross head 45 is slidably arranged between ways 46 secured to the frame, and has a roller 47 mounted on a pin 48 and arranged within the groove of the cam 42. The rotation of said cam serves to reciprocate said cross head between the ways, and so cause the operation of the component parts of the machine.

75

An operating ring 49 is arranged on a raised bearing surface 50 of said bed 30, and is provided with a number of extended arms 51 of suitable length, to which upright members 52 are secured, and which are formed with a suitable cam groove which serves to control the operation of certain component parts of the mechanism. One of said uprights 52 is formed with a gear toothed portion 53, which is arranged to mesh with a rack portion 54 formed on the cross head 45. The movement of said cross head is thereby transmitted through the rack and gear to the operating ring 49, and serves to angularly reciprocate said ring. Said ring 49 is formed with an inner concentric opening in which is disposed a plate 55, which serves as a support for the table and the creasing irons, which are herein-after to be described.

85

Said plate is slidably arranged on posts 56, which are secured in a frame member 57, here shown as of substantially cross shaped form, and which is secured to the bed 30 of the machine by suitable bolts 58. The movement of said plate 55 is under the control of the operating ring, as will be hereinafter more fully described. Said plate 55, as here shown, is formed with radially extended arms 60 at right angles to each other, in which are formed the slots 61.

90

The material table, of which a partial sectional view is shown in Fig. 9, comprises a table portion 62 to the under side of which is secured downwardly extending rods 63, which are slidably arranged in the supports 64. Springs 65 are interposed between said supports 64 and the table, and said rods 63 are provided with nuts 65', which limit the upward movement of the table. As the machine is adapted to operate on work of various dimensions, a separate table portion 110 must be provided for each different dimension of material, this table portion comprising the plate 62 with the downwardly extended rods 63. The supports 64 for said table are adjustably arranged in slots 61 of the plate 55, the base of each support being formed with a tongue 66, which extends within the groove, and a flange portion 67, which extends beyond the groove and in sliding engagement with the face of the 115

120

125

130

plate 55. A bolt 68 serves to secure a support 64 in adjusted position with respect to said plate.

By the provision of the adjustable supports 64 the table construction is materially simplified and cheaped, inasmuch as the same supports may be used for all sizes of tables, the only necessary new part being the table portion 62.

10 The material to be folded is adapted to be placed on the table 62 and to be clamped to said table by a clamping plate secured to the presser head, which is arranged above the material table and the other component 15 parts of the apparatus and secured to the presser frame.

The presser frame is formed as a unitary structure, having a rear portion 69 and the two arms 70 extending therefrom to the 20 presser head 71. The presser head is arranged to support the clamping plate and the edge formers or fold defining means, as will be hereinafter more fully explained. Said rear portion 69 of the presser frame is 25 fixed to two upright rods 72, which are slidably arranged in the base 30 of the machine. A cross member 74 is also fixed on said rods beneath the top plate of said presser frame, and carries a pin 75 which 30 is disposed in the cam groove 76 of the upright 52 secured to the operating ring 49. Said cam groove is shown in detail in Fig. 5.

The position of said member 74 is controlled by the cam groove 76 in the upright 35 52 of the operating ring, and a movement of said operating ring in such direction as to lower said cross member 74, serves to slide the two vertical rods 72 in their bearing surfaces in the frame of the machine 40 to correspondly lower the presser frame fixed to said rods to cause the engagement of the material placed on the table 62 by the clamping plate carried by the presser head.

The machine is arranged for the folding 45 of the four sides of the material and the four corners of the material, and for this purpose is provided with side wipers 77 and with corner wipers 78. Said wipers 77 and 50 78 are arranged to be moved in toward the table 62 to fold the edge of the material. The movement of said side wipers is controlled by cam slots 79 in the face portion of said uprights 52 secured to the operating ring, and the movement of the corner wipers 55 is controlled by the cam slots 80 in the face of the uprights 52' secured to the operating ring.

A rectangular shaped plate 81 is arranged on suitable supports from the base 30 of 60 the machine, and forms part of the framework of said machine.

Wiper operating members 82 are arranged in grooves 83 in said frame, and have pins 65 84, which extend downwardly therefrom through slots 85 in the frame 81 and into

engagement with the walls of the cam grooves 79 and 80 in the uprights 52 and 52'. Connecting rods or strips 86 extend between and are secured to said wiper operating members 82 and the wipers 77 and 78.

By the arrangement of the cam grooves 79 and 80, it is seen by the reciprocating angular movement of the operating ring that the wiper operating members 82 will be reciprocated with respect to said frame 81, 75 and consequently reciprocate said wipers toward and away from the material arranged on the table 62. Said connecting rods or members 86 are formed with slots 87 therein, through which screws 88 are passed to secure said connecting rods to the wiper operating members 82. By the arrangement of this slotted connection the connecting rods may be moved in toward the centre of the machine and away from the center of the 80 machine to adjust the wipers for various dimensions of material to be folded, and thereby forms an adjustable feature of the machine.

The wipers are supported on and between 85 wiper supports, which in turn are arranged on the longitudinal cross bars 89 and transverse bars 90. Said bars 89 are tongued at their extremities, and are slidably arranged in grooves 91 formed in the inner 90 part of the rectangular frame 81. Said bars are so arranged that they may move with respect to each other; that is the bars 90 may be moved with respect to the bars 89, or the bars 89 may be moved with respect to 100 the bars 90, and provide means for spacing the wipers for various dimensions of material to be folded. Rods 92 are arranged in spaced relation beneath the bars 89 and are secured to the ends of said bars by bolts 95, and 105 other rods 94 are extended beneath the bars 90, and are similarly secured to the ends of said bars by means of bolts 93. Said rods 92 and 94 form in effect parts of the said bars 89 and 90, upon which the wiper supports are adjustably arranged and form 110 means to stiffen said bars.

The wiper supports are slidably arranged on said bars 89 and 90, and rods 92 and 94, and comprise the blocks 96 formed with 115 spaced apart upright ears 97, which provide grooves in the top faces of said block 96 arranged to receive said cross bars 89 and 90. A cover plate 98 is arranged over the top of said lugs 97 and secured thereto by 120 suitable screws, and thereby forms means enclosing said plates 89 and 90 within said wiper supports. Inasmuch as certain of the screws which secure the cover plate 98 to the wiper supports must pass through either the longitudinal bars 89 or the transverse bars 90 in order to engage with the lugs 97 of the wiper support, it is necessary that slots 99 be formed in said bars to permit the desired movement of the wiper support. 125 130

As a screw 100, securing the cover plate to the block 96 passes through the transverse bar 90 to engage the block 96 and said block must be arranged for movement along said bar 90, it follows of necessity that a slot must be formed in said bar to permit such movement. In the same manner, a second screw 101, which passes through one of said longitudinal bars 89 must also operate in a slot to permit the desired movement of said wiper support along said bars 89. It may be seen that in the provision of such an adjustment the wipers may be moved toward or away from the centre of the machine to thereby adjust the machine for operation upon material of various dimensions.

The side wipers 77 are formed with tapered edges 102, which engage correspondingly tapered grooves 103 in the cover plates 98 of the wiper supports, which form means whereby the wipers may be reciprocated to and form the center of the machine, and also form means preventing the unintentional removal of said wipers from the wiper supports. As said wiper supports are moved from one adjusted position to another to accommodate the machine for operation upon material of various sizes, it is seen that the wiper suitable for one size of material will, in the new adjusted position of the wiper supports, be either too small or too large for the machine in its new set position; and, therefore, separate wipers must be supplied for every size of material which may be operated upon by the machine.

The corner wipers 78 are similarly formed with tapered sides 104, which are slidably arranged in correspondingly tapered grooves 105 diagonally arranged in the cover plates 98 of the wiper supports, and are adjustably connected to the corner wiper operating members by means of the connecting rods 86, as has been previously described. The wiping end 106 of the corner wipers is recessed or curved in form to approximately conform to the corner of the desired edge of the article operated on.

Said adjustable longitudinal and transverse bars 89 and 90 form means defining the dimensions of the folded material. The dimensions of the space enclosed by the opposing edges of said bars is arranged to be but slightly greater than the dimensions of the extended forming plates which are adapted to be inserted therein for the folding of the material, said increase of dimensions being merely that necessary to accommodate the material to be folded. In the operation of folding the material, the clamping plates force of the material into the space between the bars and the edge of the material is bent upward by said bars. The wipers are arranged to be inset from the edge of said bars previous to their wiping operation. By moving the bars toward or

away from each other the size of the opening bounded by said bars is varied for the folding of material to differing dimensions.

In the operation of the machine the side wipers are first moved into operated position to fold over the side edges of the article, and then the corner wipers are moved into operated position. After the side wipers have operated to fold the straight sides of the material a superfluity of material is gathered at the corners which in the folding movement of the corner wipers forms wrinkles, which must be taken care of and folded firmly and securely down over the edge of the material. For this purpose it has been found to be of advantage to form the wiping edge of the corner wipers with a number of small slots 107 into which the wrinkles of the material in the corner folding operation are adapted to enter. Additional means are provided for folding these wrinkles to the main body of material after the main portion of the corner has been folded. These means comprise a spring 108, which is secured to the corner wipers by suitable means, and which has a number of teeth 109 which are arranged within the slots 107. A rod 110 is extended over the corner wipers and secured by means of screws 111 to the wiper supports. The spring 108 is arranged with an upwardly bent portion 112 under which, in the extended position of the wiper, said rod 110 is adapted to lie; by which arrangement the teeth 109 of said spring are permitted to occupy the lowest position in the slots 107 of the corner wipers.

In the withdrawn position of the corner wipers, as shown in Fig. 12, said rod 110 serves to move said spring upwardly, and to partially withdraw the teeth 109 from the slots 107. As said corner wipers are moved inwardly in the process of folding the corners of the material, the teeth of said springs are maintained in elevated position by said rod 110, and the corner of the material is folded and the wrinkles form in the slots 107. Upon a further movement of said corner wipers, the bend 112 in the spring passes over said rod 110 and thereby permits the teeth 109 of the spring to be moved into their fullest downward position, and to press the wrinkles out of the slots 107 whereupon, after further movement of the corner wipers they are pressed out. The fully operated position of the corner wiper is shown in Fig. 13.

The presser head 71, between which and the table 62 the material operated upon is adapted to be clamped, is arranged on the ends of the arms 70 of the presser frame. Said arms 70 at their extremities are arranged in parallel relation, and are formed with tapered portions 113, which form ways upon which the presser head is arranged.

Said presser head is formed as a frame, having the side and end portions 114 and 115 respectively, and is approximately over the material operated on. The end portions 115 of said presser head are formed with gibs 116, which engage the tapered surfaces 113 of the parallel portions of said arms 70, and the presser head is secured to said arms by the set screws 117. Said arrangement of connection between the presser head and the arms 70 forms a convenient means for detachably connecting said head with said arms, and facilitates the exchange of a presser head of one size for a presser head of another size to accommodate material of various dimensions. The presser head 71 at its lower portion carries a clamping plate 118, which is of the general outline of the presser head, and which is secured thereto by rivets 119 and maintained in spaced relation from said presser head, whereby a space is provided between the presser head and the clamping plate 118 in which the forming plates are arranged.

For forming plates 120 are provided, the projecting portions of which are tapered to a thin edge, and which are arranged at the four corners of the presser head. Said forming plates are each arranged to present a corner and approximately half of contiguous sides of the folding edge, and in their extended position, as shown in Fig. 16, are arranged to slightly overlap, in order that an unbroken folding edge may be defined. Substantially parallel slots 121 are formed in said forming plates, and rollers 122 are arranged therein over certain of rivets 119, which serve to secure the clamping plate to the presser head. Said parallel slots 121 serve as means whereby the forming plates may be moved diagonally outwardly and inwardly.

Within the presser head the forming plate is provided with a reinforced portion or lug 123, which serves to stiffen the plates and also provides a means for the engagement of said plates with means to move said plates. A rod 124 is arranged in said lug 123, and is slidably extended through the presser head 71, and serves as a guide for said forming plates in addition to the slots 121 in said plates, and also serves to strengthen said plates in their extended position. Blocks 125 are arranged within the presser head, and are formed with slots 126 therein which are arranged to move at substantially right angles to the direction of movement of said forming plates. The lugs 123 of said forming plates bear upwardly extended pins 127 over which are disposed rollers 128 arranged in said slots 126. A movement of said blocks 125 inwardly within said presser head serves to withdraw said forming plate simultaneously from extended position. Said blocks 125 are arranged

to be simultaneously operated by a slide 129 arranged within the parallel portion of said arms 70. Said slide is formed at the end remote from the presser head with an extended ear or lug 130, through which is arranged the operating rod 131 to which said slide is secured by means of set screw 132.

Said rod 131 extends through and is slidably arranged in a cross member 133 uniting said arms 70 at the presser head, and is slidably arranged in and extends through the rear portion 69 of said presser frame, and serves as a means whereby said slide is moved to extend or withdraw the forming plates. A spring 134 is arranged on said rod 131 between the lug 130 of the slide 129 and the connecting member 133 of the arms 70, and serves to normally press said slide 129 in a direction to extend the forming plates into their operative and fold defining position.

A collar 135 is secured on said shaft 131, and engages with the end portion 69 of said presser frame to limit the spring pressed movement of said rod 131. The slide 129 is formed with right angularly disposed slots 136. Pins 137 are upwardly extended from said sliding blocks 125, and have secured thereon rollers 138, which are arranged in said slots 136 of the slide. An outward movement of said slide in the presser head serves to move said sliding blocks 125 inwardly, which blocks in turn operate through the slots 126 therein and the rollers 127 secured to the forming plates to move said forming plates simultaneously inward to the retracted position, and the reverse movement of said slide 129 operates in reverse sense to extend the forming plates into their fold defining position.

The rod 131 is operated by the cam block 139 bearing the cam surface 140 secured to the sliding cross head 45. A pin 141 is secured to the end of said rod 131 by suitable means. As the forming plates are normally extended in their fold defining position, said cam surface 140 is arranged to permit considerable movement of said cross head without operating said rod 131 to permit the operation of other parts of the machine; but upon a continued movement of the cross head, said cam surface is arranged to move said rod 131 inwardly to cause the retraction of the forming plates, and after said retraction the forming plates are locked in retracted position during subsequent operations of component parts of the machine.

Inasmuch as the forming plates are in extended position when the wipers are operated to fold the material over said forming plates, and as the return movements of the component parts of the elements thereof to condition the machine for a new operation are in exactly the reverse order to their initial operation it is seen that the forming

6
plates may be in an extended position and moved upward while the wipers are also extended above said plates and that consequently the machine may become seriously 5 damaged if means are not provided to lock said forming plates in retracted position until the component parts of the machine have returned to their initial positions in readiness for a new operation.

10 Said locking means comprises a bolt 142 slidably arranged within suitable bearings 143 secured to the rear portion 69 of the presser frame. A retractal spring 144, connected between said bolt and said frame 15 serves to normally press the end of said bolt into a notch 145 in said rod 131.

In the retracted position of the forming plates said bolt 142 is moved under action of the spring 144 into engagement with said 20 notch 145 and serves to lock said rod in the retracted position of the forming plates. Unlocking means are provided, which are adapted to be operated only when the various parts of the folding machine are moved 25 to their original and normal position. Said unlocking means includes an upright member 146 secured to the end of the sliding cross 45. The bolt 142 is provided with a downwardly extended lug 147 in which is 30 arranged an adjustable bolt or screw 148 which extends in the path of movement of said lug 146. When said cross head has been moved by its operating cam into nearly its initial position, said lug 146 is adapted to 35 engage the screw 148 and to retract the bolt 142 from engagement with the slot 145 of the rod 131, which operates the slide controlling the movement of the forming plates. Said rod 131 and the slide secured thereto 40 are thereupon returned to its normal position by the spring 134, and the forming plates are thereupon extended to the fold defining position in readiness for another operation.

45 Creasing means are arranged beneath the material table 62, and are arranged to engage with the material operated upon during the completion of the fold. Said creasing means comprises corner supports 148' bearing creasing irons 149 and side creasing irons 150. Certain of said corner supports are arranged to be heated by some means conveniently shown by the electric heating coils 152 to thereby heat the creasing iron. It is sufficient to apply the heating means 50 locally to the creasing iron, as the heat will be conducted to the entire creasing edge more or less uniformly.

55 Inasmuch as the machine is adapted to operate upon material of various sizes, and 60 as the crease formed in the folded material conforms very closely to the edge of said material, it is necessary that said creasing means may be arranged to accommodate the various dimensions of material operated upon. By the provision of corner supports

bearing creasing irons 149, and separate side creasing irons 150, it may be seen that the corner supports and associated corner creasing irons may be moved closer together or farther apart, and the desired shape of 70 crease produced by the substitution of side creasing irons of certain dimensions for those of other dimensions to accommodate for the difference in dimension of material 75 worked upon.

Said corner supports are formed with grooved portions 153, into which the side creasing irons 150 are adapted to fit. Said supports are arranged in pairs on the rods 154, and may be adjusted relative to each 80 other along said rods. The bases of said supports are formed with gibbed grooves 155 therein, arranged transverse of the length of the rods 154 and bars 156 with tapered edges to fit the gibs of said grooves, 85 are disposed within said grooves. The arrangement of said rods 154 and bars 156 at right angles to each other, provides means whereby the supports may be adjusted inwardly or outwardly to provide for the 90 creasing of material to differing dimensions. Said corner supports are adapted to be secured to said bars 156 and rods 154 by means of the set screws 157. The creasing means, as a whole, is secured to the plate 95 55 by means having provision for the vertical adjustment of said creasing means with respect to said plate, whereby the depth of the crease in the material may be adjusted.

100 For this purpose two blocks 158 are arranged on arms 60 of said plate 55, and are formed with tongues 159 which extend within the slot 61 of said arms. Plates 160 are secured to the bars 156, and are formed with 105 grooves 161 therein. Said blocks 158 are formed with tapered grooves therein, which correspond to the grooves in the plates 160. Tapered keys 162 are arranged in said 110 grooves and serve to unite said plates 160 with said blocks 158; and a movement of 115 said keys with respect to said blocks and plate, serves to adjust the vertical position of the creasing iron. The keys 162 are formed with downwardly extended ears 163, which engage the groove 164 of a bolt 165 120 threaded within the blocks 158. By turning the bolt 165, the key 162 may be moved within the grooves within said plates 160 and blocks 158 to adjust the vertical position of the creasing iron.

125 Bolts 166 extend through said plates 160 and blocks 158 and terminate in wing nuts 167, which engage the arms 60 and serve to clamp the creasing iron in any adjusted position. The creasing irons are arranged to be moved into engagement with the folded edge of the material during the latter part of the folding operation. For this purpose the end of said arms 60 of the plate 55 are formed with a cam groove 168 therein, the 130

shape of which cam is shown in detail in Fig. 6.

Pins 169 are secured in the operating ring 49 and extend into said cam grooves. The 5 shape of the cams is such that during a certain movement of the operating ring, the plate 55 is maintained stationary and is supported in its normal position by its engagement with said pins 169.

10 When the operating ring 49 has reached the position at which it is desired that the creasing iron be brought into engagement with the material operated upon, the shape of the cam grooves is such that the pin 169 raises said plate 55 and thereby the creasing iron into engagement with the material operated upon, and said creasing iron is held in such engagement during the passage of the second dwell 15 portion of the cam path 43 by the cam roll 47 of the cross-head 45 and for a sufficient period of time to obtain a good crease. Upon the reversal of movement of the operating ring 49 the plate 55 is moved 20 downward to its original position.

In the normal arrangement of the component parts of the machine with the clutch thrown out, the presser head is raised from engagement with the material table, and the 25 forming plates are extended to define the folding edge, and the wiper plates are withdrawn. The material to be folded is placed on the table under the clamping plate, and the clutch lever is thrown to cause the engagement of the clutch with the driving 30 mechanism. The cam 42 consequently revolves and causes the cross head 45 to move transversely of the machine, thereby transmitting the motion to the operating ring 49. 35 The movement of the operating ring 49 causes an immediate downward movement of the cross connecting member 74 because of the engagement of the pin 75 carried thereby with the steep part 170 of the cam groove 76, and thereby causes the presser frame to descend and move the clamping plate into engagement with the material on the table 62 and to secure said material to 40 said plate.

45 The cam shape is so arranged that the table 62 is moved downward to some point below the wipers 77, and the edge of the material is bent upward by said bars 89 and 90. The cam groove 76 controlling the movement of said presser frame is provided with a dwell portion 171, whereby the presser frame may remain without motion upon the continued motion of the operating ring 49 in the original direction. The side 50 wipers are now moved inward by the cams 79 arranged in the uprights 52 secured to the operating ring, and serve to fold the material over the extended forming plates. A further movement of the operating ring 55 causes the operation of the corner wipers

through the cam grooves 80 arranged in the uprights 52' over the extended forming plates.

The dwell portions 172 and 173 of said cam grooves 79 and 80 are of such a length 70 that the presser frame may be moved into engagement with the table to clamp the material thereto, without a movement of the side wipers; and the dwell portions 173 of the cam grooves 80 are of such a length that 75 the side wipers are operated before the corner wipers.

The cam groove 140 in the block 139 secured to the cross head 45, upon the continued movement of the operating ring, now 80 operates to cause the withdrawal of the forming plates from extended position, and said forming plates are locked in retracted position by the locking means previously described. The continued movement of the operating ring now serves to move the cam groove 76 controlling the operation of the presser frame to the raised portion 174, which serves to raise the clamping plate a slight amount from the table and permits 85 the folded edge to be brought into engagement with the under side of the wipers 77, and thereby serves to unite the folded edge with the body of the material, which edge has been previously coated with an adhesive. 90

Upon the continued movement of the operating ring 49, the creasing iron is arranged to be moved upwardly into engagement with the folded edge, and the cam groove 168 arranged in the ends of the arms 60 of the 100 plate 55 upon which the creasing iron is supported is so formed as to compel this movement.

Said cam grooves 168 are so formed that the previous movement of the operating ring 105 has been ineffective in causing the plate 55 to be raised.

The material operated upon has now been folded and creased, and the continued movement of the cam 42 serves to return the sliding cross head 45 towards its original position, and serves to withdraw the creasing iron from engagement with the material, to lower the clamping plate and material from engagement with the wipers, to withdraw the corner wipers and the side wipers to their normal position, and to finally raise the presser frame to elevated position to unlock the forming plates, which return to their extended and fold defining position, 110 whereupon the machine is conditioned for another operation, and the material operated upon may be withdrawn from between the table and the clamping plate, and another article may be inserted therebetween to be 115 folded and creased.

I claim:

1. In a material folding machine, material clamping means, fold defining means, folding means and adjustable creasing 120

means to permit the creasing of material folded to differing dimensions.

2. In a machine for folding material to differing dimensions of creasing means and means to adjust said creasing means to form creases of differing dimensions on the material.

3. In a material folding machine, material clamping means, forming plates to simultaneously define the line of fold on the sides and corners of the material, side wipers operable to fold the side edges of the material and corner wipers subsequently operable to fold the corners of the material.

15 4. In a material folding machine, material clamping means, fold defining means, edge folding means, and a creasing iron movable into engagement with the material to form a crease therein.

20 5. In a material folding machine, material clamping means, fold defining means, normally extended to define the line of fold, edge folding means, material creasing means, and means to successively operate the clamping means, cause the withdrawal of the fold defining means from the line of fold, operate the edge folding means, and cause the engagement of the creasing means with the material.

30 6. In a material folding machine, folding means, and an angularly reciprocable operating ring formed with cam surfaces engageable with said folding means to effect the operation thereof.

35 7. In a material folding machine, an angularly reciprocable operating ring, and a reciprocating sliding block arranged to reciprocate said operating ring angularly.

40 8. In a material folding machine, an angularly reciprocable operating ring, and a reciprocating sliding block arranged to reciprocate said operating ring angularly and a cam member engageable with said sliding block to reciprocate it.

45 9. In a material folding machine, an angularly reciprocable operating ring having gear teeth, and means to reciprocate said ring angularly including a block arranged for sliding movement having gear teeth meshing with the teeth of said ring.

50 10. In a material folding machine, material clamping means, an operating ring therefor, a plate arranged within said ring, and material creasing means carried by said plate.

55 11. In a material folding machine, material clamping means, an operating ring therefor, a plate arranged within said ring, creasing means arranged on said plate, and means to move said plate to cause the operation of the creasing means.

60 12. In a material folding machine, material clamping means, an operating ring therefor, a plate arranged within said ring, creasing means arranged on said plate, and

means to move said plate toward the material to cause the operation of the creasing means.

65 13. In a material folding machine, material clamping means, an operating ring therefor, creasing means for the material, and means connecting said operating ring and said creasing means to cause the engagement of the creasing means with the material.

70 14. In a material folding machine, material clamping means, an operating ring therefor, creasing means for the material, and a support therefor having a cam surface, said operating ring engaging with the cam surface of said support to cause said creasing means to move into engagement with the material.

75 15. In a material folding machine, an operating ring, a plate movably arranged within said ring, and a table adapted to hold the material during operation thereon supported by said plate.

80 16. In a material folding machine, material operating means, an operating ring for said means, a plate arranged within said ring, and a material table and creasing means for the material supported by said plate.

85 17. In a material folding machine, an operating ring, a plate arranged within said ring, means connecting said ring and plate for movement of said plate, a material table, and means yieldingly supporting said table on said plate.

90 18. In a material folding machine, material clamping and material folding means, a table support, and a table on which the material is adapted to be clamped carried by said support having means by which it is adjustable on said support toward and away from said clamping means.

95 19. In a material folding machine, a material table having downwardly extended extensions, and a support for said table having slots in which said extensions are arranged.

100 20. In a material folding machine, a material table, table supports and a plate on which said table supports are adjustably arranged and means to secure said supports in adjusted position on said plate.

105 21. In a material folding machine, a supporting plate, table supports arranged thereon, a material table and means to yieldingly support said table from said supports.

110 22. In a material folding machine, an operating ring therefor, a plate having slots arranged within said ring, means operably connecting said plate and ring, table supports adjustably arranged in said slots, and a material table yieldingly carried by said supports.

115 23. In a material folding machine, creasing means for the material including corner

100

125

130

- creasing irons, and separate side creasing irons associated with said corner creasing irons to form a substantially continuous creasing edge.
5. 24. In a material folding machine, creasing means for the material including corner creasing irons, and separate side creasing irons arranged for detachable connection with said corner creasing irons to form a substantially continuous creasing edge.
10. 25. In a material folding machine, material creasing means including a supporting post, and a creasing iron detachably supported thereby.
15. 26. In a material folding machine, material creasing means including a supporting post, heating means associated with said post, and a creasing iron detachably supported by said post.
20. 27. In a material folding machine, creasing means for the material including a corner creasing iron, and a side creasing iron detachably connected with said corner creasing iron.
25. 28. In a material folding machine, creasing means for the material including corner creasing irons, separate side creasing irons, and heating means for certain of said irons.
30. 29. In a material folding machine, creasing means for the material including corner creasing irons and side creasing irons, said corner creasing irons being adjustably correlated.
35. 30. In a material folding machine, creasing means for the material including relatively movable supports, means to secure said supports in fixed position, and creasing irons carried removably by said supports.
40. 31. In a material folding machine, creasing means for the material including corner creasing irons, a support for said creasing means with which said corner creasing irons are movably related and side creasing irons detachably connected to said corner creasing irons.
45. 32. In a material folding machine, creasing means for the material, a support therefor, and means to adjust said creasing means relative to said support.
50. 33. In a material folding machine, creasing means for the material having a creasing edge, a support therefor, and means to adjust said creasing edge for height above said support.
55. 34. In a material creasing folding machine, creasing means including corner creasing irons adjustably connected in groups and means connecting said groups permitting relative motion therebetween.
60. 35. In a material folding machine, clamping means, edge folding means, operating means for the aforesaid means, and edge folding supporting means adjustably related with respect to said clamping means.
65. 36. In a material folding machine, clamp-
ing means, and wipers for folding the edge, and means to adjust said wipers for the folding of differing dimensions of material.
37. In a material folding machine, material folding means comprising a plurality of angularly related wipers, means to adjust said wipers toward or away from each other to enclose a lesser or greater folding space for the folding of material of differing dimensions, and means to reciprocate said wipers in adjusted positions thereof. 70
38. In a material folding machine, material clamping means, a wiper for folding the material, a reciprocating element for operating the wiper, said wiper adjustable toward or away from said element for the folding of material to differing dimensions, and means adjustably connecting said wiper with said element for the reciprocation of said wiper in adjusted position thereof for operation on material for the folding thereof to differing dimensions. 80
39. In a material folding machine, material clamping means, wipers for folding the material, and wiper supports relatively movable to adjust the machine for operation upon material of differing dimensions. 90
40. In a material folding machine, wiper supports, material clamping means arranged between said supports and wipers slidably arranged on said supports. 95
41. In a material folding machine, material clamping means, wiper supports, side wipers slidably arranged between said supports, and corner wipers carried by said supports. 100
42. In a material folding machine, material clamping means, wiper supports arranged at the corners of the material to be folded, corner wipers carried by said supports to fold the corners of the material, and side wipers slidably arranged between said supports to fold the sides of the material. 105
43. In a material folding machine, material clamping means, wiper supports arranged at the corners of the material and movable toward or away from the clamping means to adjust the machine for operation upon material of varying dimensions, and wipers to fold the material carried by said supports. 110
44. In a material folding machine, a supporting frame, material clamping means, wiper supports, wipers supported thereby to fold the material and bars slidably arranged on said frame, said wiper supports being slidably arranged on said bars whereby said wipers may be adjusted with respect to the clamping means to adjust the machine for folding material to differing dimensions. 120
45. In a material folding machine, a supporting frame, material clamping means, wiper supports, wipers supported thereby to fold the material, longitudinal bars slidably arranged on said supporting frame 125
- 130

- and transverse bars slidably arranged on said frame, said wiper supports being slidably arranged on said bars whereby said wipers may be adjusted to fold the material to differing dimensions.
46. In a material folding machine, a supporting frame, material clamping means, wiper supports, wipers supported thereby to fold the material, and longitudinal and transverse bars slidably arranged on said frame, said wiper supports being slidably supported on said longitudinal and transverse bars whereby said wipers may be adjusted to fold the material to differing dimensions.
47. In a folding machine, material clamping means, side and corner wipers arranged about said clamping means to fold the material, and an operating ring therefor having cam surfaces to operate the side wipers, and separate cam surfaces to operate the corner wipers subsequent to the operation of the side wipers for the folding of the material.
48. In a folding machine having material clamping and fold defining means, a corner wiper to fold a corner of the material, said corner wiper having slots therein to receive the wrinkles of material formed during the folding operation.
49. In a folding machine having material clamping and fold defining means, a corner wiper to fold a corner of the material permitting the formation of wrinkles during the corner folding operation, and means to press said wrinkles on to the body of the material.
50. In a folding machine having material clamping and fold defining means, a corner wiper to fold a corner of the material permitting the formation of wrinkles during the corner folding operation, and means to press out said wrinkles subsequent to the initial folding movement.
51. In a folding machine having material clamping and fold defining means, a corner wiper to fold a corner of the material having a wiping face shaped to conform to the folded corner, and having slots therein to receive the wrinkles formed during the folding operation.
52. In a folding machine having material clamping and fold defining means, a corner wiper to fold a corner of the material having slots in its wiping face, to receive the wrinkles formed in the folding of the material, and means to press the wrinkles on to the fold.
53. In a folding machine having material clamping and fold defining means, a corner wiper to fold a corner of the material having slots in its wiping face, to receive the wrinkles formed in the folding of the material, and means operating in said slots to press the wrinkles on to the fold.
54. In a folding machine having material clamping and fold defining means a corner wiper to fold a corner of the material having slots in its wiping face to receive the wrinkles formed in the folding of the material, and spring pressed members operating in the slots to press the wrinkles onto the fold.
55. In a folding machine having material clamping and fold defining means, a corner wiper to fold a corner of the material having slots in its wiping face to receive the wrinkles formed in the folding of the material, and spring pressed members operating in the slots to press the wrinkles onto the fold, means to raise said members from engagement with the material during a part of the folding movement and thereafter permitting said members to engage the material during the completion of the folding movement of said wiper to press the wrinkles onto the body of the material.
56. In a material folding machine, a base, rods carried by said base at one side thereof and extended thereabove, a pressure arm supported by said rods and extended over said base, and means to move said arm toward or from said base.
57. In a material folding machine, a base, material operating devices carried by said base, guide rods supported for vertical movement in and extended above said base at one side of said material-operating devices, a presser-arm secured to said rods and extended over said base and said material-operating devices, and means to support said presser-arm yieldingly in raised position including a spring encircling one of said rods and arranged to engage said base and presser-arm.
58. In a material folding machine, clamping means between which the material is clamped during the folding operation, wipers extended to fold the material, means to press the folded edge and wipers into engagement to secure the fold to the body of the material, said wipers being retracted after the pressing operation, and means to cause the disengagement of the material and wipers previous to the retraction of said wipers.
59. In a folding machine, a material table, a clamping plate between which and the table the material is adapted to be secured, and a support to which said clamping plate is detachably secured whereby clamping plates of differing dimensions may be arranged thereon for the folding of material to differing dimensions.
60. In a folding machine, a material table, a presser head bearing a clamping plate arranged above said table and between which and the table the material is adapted to be secured, and a support to which said presser head is detachably secured whereby presser heads of differing dimensions may

be arranged thereon for the folding of material to differing dimensions.

61. In a folding machine, a material table, a presser head disposed above said table, a clamping plate and a forming plate carried by said presser head, and a support to which said presser head is detachably secured.

62. In a folding machine, a material table, a presser head arranged above said table, a clamping plate carried by said presser head to clamp the material to said table, forming plates carried by said presser head above said clamping plate movable to present a line of fold beyond the edge of said clamping plate and movable to a retracted position, and a support for said presser head.

63. In a folding machine, a material table, a presser head arranged above said table, a clamping plate carried by said presser head to clamp the material to said table, forming plates carried by said presser head and diagonally movable with respect thereto to present a line of fold, and operating means for said forming plates.

64. In a folding machine, a material table, a presser head movably arranged above said table, a clamping plate secured to said presser head, forming plates carried by said presser head movable with respect to said clamping plate, blocks slidably arranged in said presser head connected with said forming plates to extend and retract said forming plates, and operating means for said sliding blocks.

65. In a folding machine, a material table, a presser head movably arranged above said table, a clamping plate secured to said presser head, forming plates carried by said presser head movable with respect to said clamping plate, blocks slidably arranged in said presser head connected with said forming plates to extend and retract said forming plates, and means to operate said sliding blocks to simultaneously expand and contract said forming plates.

66. In a folding machine, a material table, a presser head movably arranged above said table, a clamping plate secured to said presser head, forming plates carried by said presser head movable with respect to said clamping plate, blocks slidably arranged in said presser head having cam surfaces connecting with said forming plates to extend or retract said plates, and a sliding member having cam grooves connecting with said sliding blocks operable to cause the extension or retraction of said forming plates.

67. In a folding machine arranged for the folding of material to differing dimensions, a material table, a presser head between which and said table the material is adapted to be clamped for the folding operation,

and means admitting the interchange of presser heads of differing dimensions to permit the folding of material to differing dimensions.

68. In a folding machine arranged for the folding of material to differing dimensions, a material table, forming plates to define a line of fold, and means admitting the interchange of forming plates to define lines of fold of differing dimensions to permit the folding of material of differing dimensions.

69. In a folding machine arranged for the folding of material to differing dimensions, material clamping means, means to define a line of fold, wipers to fold the material and means admitting the interchange of wipers to permit the folding of material to differing dimensions.

70. In a folding machine arranged for the folding of material to differing dimensions, means to define a line of fold, means to fold the material, a table to which the material is adapted to be secured for the folding operation, and means admitting the interchange of tables of differing dimensions to permit the folding of material to differing dimensions.

71. In a folding machine arranged for the folding of material to differing dimensions, material clamping means, means to define a line of fold, means to fold the material, creasing irons to crease the material, and means admitting the interchange of creasing irons to permit the creasing of material of differing dimensions.

72. In a folding machine arranged for the folding of material to differing dimensions, material clamping means, means to define the line of fold, means to fold the material, and means whereby the folding means may be adjusted for the folding of material to differing dimensions.

73. In a folding machine arranged for the folding of material to differing dimensions, material clamping means, means to fold the material, forming plates movable to define the line of fold, means detachably securing said forming plates to the machine admitting of the interchange of forming plates to permit the defining of material to differing dimensions, a slide operable to move said forming plates, and an operating member for said slide, said slide being adjustably connected to said member to permit the adjustment of said member to permit the adjustment of said slide for forming plates of differing dimensions.

In testimony whereof, I have signed my name to this specification, in the presence of two subscribing witnesses.

JOSEPH W. ANTHONY.
